W. M. STANBROUGH

UPPER DENTAL PLATE

Filed Feb. 23. 1922

Fig. 1.

WILLIAM MONELL STANBROUGH,

INVENTOR

BY *L. Steven Lattie*

As his ATTORNEY.

UNITED STATES PATENT OFFICE.

WILLIAM M. STANBROUGH, OF NEWBURGH, NEW YORK.

UPPER DENTAL PLATE.

Application filed February 23, 1922. Serial No. 538,778.

To all whom it may concern:

Be it known that I, WILLIAM MONELL STANBROUGH, a citizen of the United States, and a resident of Newburgh, county of Orange, and State of New York, have invented certain new and useful Improvements in Upper Dental Plates; and I do hereby declare the following to be a full, clear, and exact description of the invention, such as will enable others skilled in the art to which it appertains to make and use the same.

My invention consists of the novel features hereinafter described, references being had to the accompanying drawing which will illustrate the method I use in one embodiment of the invention, and is selected by me for the purpose of illustration. My said invention is fully disclosed in the following description and claim.

The object of my invention is to provide a means of adjusting full upper dentures to meet the changed condition brought about by a resorption of the alveola ridge following the extraction of the teeth, and which progresses more rapidly after artificial dentures are placed in the mouth. This change in the size of the tissue covered by the artificial denture has been and is a source of disturbance to both the dentist and the patient, resulting in a loss of the retaining powers. As the resorption or shrinkage progresses, the denture bears heavily upon the median line of the hard palate resulting in a fulcrum at that point which serves to tip the plate and results in destroying the valvular effect desired and the seal being broken, results in gravity tending to drop the denture.

To meet and overcome this condition is the object of my invention, and I will describe some of the preferred methods I have employed in accomplishing the desired results.

Figure 1 shows a cross section in a vertical plane through an upper denture in place.

Referring to the drawing in detail, one means of meeting change in size of tissue supporting an artificial denture, which change increased the bearing at the hard palate "A" to an undesirable extent, has been met in the past by cutting away a portion of the plate in contact with "A" by means of scrapers, files, burrs, or sand paper, and has resulted in an uneven removal of material.

To meet this change in tissue size, which always occurs to a greater or less extent, is the object sought, and I have accomplished it as follows:

I place two or more layers of pure tin upon the cast previous to packing with vulcanite rubber to form an "air chamber" "B." It has been the custom to remove all the layers of tin, but I propose to remove only the layers that are found desirable after being placed in service. Observation and study has made it plain that a so-called air chamber is not desirable, such a chamber in the palatine portion of a full plate results in the tissue being forced into the cavity which fills it, and such tissue is unhealthy and in a highly congested condition.

The plate not being in contact with the palate portion of the roof of the mouth, results in an undue pressure upon the alveola ridge "C" which results in a rapid resorption and loss of "fit" due to the breaking of the air seal "D." It will be seen that if several layers of proper material be used, means will be at hand to equalize bearing of the denture plate in a desired and beneficial way.

Another means which I employ in my methods of constructing these upper dentures, is to make the tongue aspect of an upper artificial denture of a metal such as gold or pure tin, or any approved alloy forming an "air chamber" in the usual way, but of larger size. When the denture is being fitted to the mouth, some substance such as gutta percha or other approved material may be placed in the recess and while still plastic, adjust it to the mouth. At a later date when the shrinkage has occurred and it is desirable to decrease the bearing upon the center of the hard palate "A" in order to preserve the seal "D" due to shrinkage at "C" the gutta percha or other recess filling material may be heated and an adjustment to the changed conditions made.

Another method of achieving adjustment of full upper dentures so that the changes in the alveola "C" incident to time and usage can be automatically taken care of, is to cover the palatine portion of the plate with a soft metal of approved thickness such as pure gold, or an alloy of any kind that would serve the purpose, sufficiently ductile and flexible to act as an adjusting

means as shown diagrammatically at "B" the palatine portion of said denture. This serves as an adjusting means fitted from time to time to the shape of the hard palate; 5 adjustment must be effected between excessive pressure at "A" which causes rocking of the denture, and excessive pressure at "C" which causes rapid resorption of the alveola ridge. The shape of the palatine 10 portion of the plate must adapt itself or be adapted to changed conditions in the shape of the mouth resulting in benefit to both dentist and patient.

The art of full denture construction has 15 reached a higher plane and the patient has better service from artificial dentures.

It is to be understood, and I do not limit

myself to the means described herein, but that the scope of my invention covers other means as embodied in the claim, and what 20 I claim, is:

An upper artificial denture having in combination a plate, teeth connected therewith, a palatine portion comprising a composition core, a plurality of layers of metallic foil superimposed thereon, susceptible of being severally removed by a scalpel or other instrument, substantially as and for the purposes as hereinbefore set forth. 25

In testimony whereof, I have signed my name to these specifications this 18 day of February, 1922. 30

WM. M. STANBROUGH.
